CLAIM

The ornamental design for an EARRING, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of an EARRING according to the present disclosure.

FIG. 2 is a rear view of the EARRING of FIG. 1.

FIG. 3 is a right side view of the EARRING of FIG. 1.

FIG. 4 is a left side view of the EARRING of FIG. 1.

FIG. 5 is a top view of the EARRING of FIG. 1.

FIG. 6 is a bottom view of the EARRING of FIG. 1.

FIG. 7 is a bottom front-right perspective view of the EARRING of FIG. 1.

FIG. 8 is a front view of a second embodiment of an EARRING according to the present disclosure.

FIG. 9 is a rear view of the EARRING of FIG. 8.

FIG. 10 is a right side view of the EARRING of FIG. 8.

FIG. 11 is a left side view of the EARRING of FIG. 8.

FIG. 12 is a top view of the EARRING of FIG. 8.

FIG. 13 is a bottom view of the EARRING of FIG. 8.

FIG. 14 is a bottom front-right perspective view of the EARRING of FIG. 8.
